(57) **CLAIM**

We claim the ornamental design for a display stand, as shown and described.

DESCRIPTION

FIG. 1 is a perspective view of our design of a display stand according to our invention;

FIG. 2 is a top plan view of the display stand shown in FIG. 1;

FIG. 3 is a bottom plan view of the display stand shown in FIG. 1;

FIG. 4 is a left side view of the display stand shown in FIG. 1;

FIG. 5 is a right side view of the display stand shown in FIG. 1;

FIG. 6 is a front view of the display stand shown in FIG. 1;

FIG. 7 is a rear view of a display stand shown in FIG. 1;

FIG. 8 is a perspective view of the display stand shown in FIG. 1;

FIG. 9 is a perspective view of our design of a display stand according to our invention;

FIG. 10 is a top plan view of the display stand shown in FIG. 9;

FIG. 11 is a bottom plan view of the display stand shown in FIG. 9;

FIG. 12 is a left side view of the display stand shown in FIG. 9;

FIG. 13 is a right side view of the display stand shown in FIG. 9;

FIG. 14 is a front view of the display stand shown in FIG. 9;

FIG. 15 is a rear view of a display stand shown in FIG. 9; and,

FIG. 16 is a perspective view of the display stand shown in FIG. 9.

The broken lines depict portions of the display stand that form no part of the claimed design. The bold, wavy lines do

(Continued)

not constitute a feature of the claimed design, and are included for illustrative purposes only in order to define the boundary of the design.
